UNITED STATES PATENT OFFICE.

JAMES B. FOOTE, OF FREDERICKTOWN, OHIO.

DESIGN FOR A CARRIAGE-JACK.

SPECIFICATION forming part of Design No. 27,812, dated November 2, 1897.

Application filed July 17, 1897. Serial No. 644,991. Term of patent 3½ years.

To all whom it may concern:

Be it known that I, JAMES B. FOOTE, a citizen of the United States, and a resident of Fredericktown, in the county of Knox and State of Ohio, have invented and produced a new and useful Design for Carriage-Jacks; and I do hereby declare that the following is a full, clear, and exact description of the invention, which will enable others skilled in the art to which it appertains to make and use the same, reference being had to the accompanying drawings, which form a part of this specification.

My invention relates to an improved carriage-jack; and its leading feature consists in the peculiar configuration and ornamental appearance given thereto.

In the accompanying drawings, Figure 1 is a perspective view of a carriage-jack constructed according to my design. Fig. 2 is a side elevation. Fig. 3 is a cross-section on the line xx , Fig. 2. Fig. 4 is a similar view on the line yy , Fig. 2.

Referring to said drawings, the numeral 1 designates a cylindrical portion having an in-

wardly-projecting portion 2 at right angles thereto and formed at the end with a jaw 3. At the other end there is formed with said cylindrical portion an inclined portion 4 and a horizontal portion 5 in a plane parallel with said portion 1, an inwardly-inclined portion 6, an oppositely-inclined portion 7, and a horizontal portion 8, having a lug 9 at the end. The portions 4, 5, 6, and 7 are formed with openings 10, which give them a very ornamental appearance, and at the junction of the portions 6 and 7 is an outwardly-extending ornamental handle 12.

Having thus fully described my invention, what I claim is—

The design for a carriage-jack, as herein shown and described.

In testimony that I claim the foregoing as my own I have hereunto affixed my signature in presence of two witnesses.

JAMES B. FOOTE.
